UNITED STATES PATENT OFFICE.

LOUIS J. HALL, OF FREEPORT, NEW YORK, ASSIGNOR TO THE MORRIS-HALL MAIL CLOSER COMPANY, OF ROCHESTER, NEW YORK, A CORPORATION OF DELAWARE.

MACHINE FOR SEALING MAIL-MATTER.

1,132,930.

Specification of Letters Patent.

Patented Mar. 23, 1915.

Original application filed June 13, 1903, Serial No. 161,280. Divided and this application filed May 20, 1911, Serial No. 628,438. Renewed August 10, 1914. Serial No. 856,109.

To all whom it may concern:

Be it known that I, LOUIS J. HALL, a citizen of the United States, now residing at Freeport, in the county of Nassau and State 5 of New York, have invented certain new and useful Improvements in Machines for Sealing Mail-Matter, of which the following is a specification.

This invention relates to machines for 10 sealing mail matter and for similar purposes, and more particularly contemplates various improvements upon and additions to the mechanisms disclosed in my prior application Serial No. 715,042, filed April 29, 15 1899, which application resulted in Patent No. 870,359, dated November 5, 1907.

The object of the invention is to provide an improved construction in machines of the character referred to, and it consists in the 20 matters hereinafter set forth and particularly pointed out in the appended claims.

This application is a division of my application filed June 13, 1903, Serial No. 161,280, for machines for stamping and 25 sealing mail matter.

In the accompanying drawings illustrative of the machine embodying my improvements in one form: Figure 1 is a plan view of the sealing mechanism, the other parts of 30 the machine not included in this application being omitted; Fig. 2 a sectional front elevation taken just inside of the front frame of the machine; Fig. 3 an enlarged detail plan of the sealing and stacking mechanism and Fig. 4 an enlarged end elevation 35 of the sealing and stacking mechanism, a portion of the holding frame being shown in vertical sectional view.

The supporting frame-work 1 of the machine, as herein shown, is made of metal plates which also serve to form a protecting inclosure for the mechanism. Extending 40 across this frame-work, from front to rear and transversely of its length, is the main driving shaft 2, one end of which projects from the plate to carry the driving connection or pulley 3 by which it may be rotated from any suitable source of power. This 45 driving shaft is formed with a crank 4 by which the carrier C is reciprocated, and also supports and drives the cam 7 which gives movement to the feeder.

The carrier C, which transfers the envelope first from the magazine to a position in front of the affixing mechanism, and then 55 from the latter position to the stacker, is herein shown as mounted to slide upon a pair of guide rods 14 which extend longitudinally of the machine parallel to its front plate 1. The base plate 15 of the carrier is 60 grooved to fit over the rods 14, as shown in my application Serial No. 161,280, and is provided on its under surface with a strap 16, which is removably secured to the carrier base by screws 17, and the ends of which 65 project beneath the guide rods and prevent the carrier from being lifted from them. The carrier is actuated from the crank 4 on the main driving shaft by a pitman 6, and makes one full reciprocation back and forth 70 with each revolution of said shaft.

The jaws 18 and 19 of the carrier on the back side of the path of the envelope are formed at the upper edge of a rigid bracket 19^a, that rises from the base plate 15 of the 75 carrier. Opposed to these rigid jaws 18 and 19, are two movable jaws 20 and 21, respectively, which are carried upon the upper ends of vibratory arms 22 and 23 that are independent of each other but are both pivoted to the same shaft carried by plate 15. The carrier is thus provided in effect with two pairs of opposing jaws, 18—20 and 19—21, respectively. And in the operation 80 of the machine, the jaws 18—20, at one end 85 of the carrier, enter the magazine and pull the envelope to a position in front of the stamp affixing mechanism (when the apparatus is used in connection with a stamp applying mechanism) in one reciprocation of 90 the carrier, while the jaws 19—21 at its other end seize the rear end of the same envelope and push it from the stamp affixing mechanism into the sealer in the next reciprocation of the carrier. 95

The lever 25 is normally maintained under pressure tending to swing it outwardly to open the jaws, by means of a spring 34 which is mounted upon a rod 35 that projects forwardly from a lug 36 on the carrier base 15, the free forward end of this rod 35 being arranged to pass loosely through the lever 25 and the spring 34 being compressed between the lug 36 and the 100

inner side of said lever. The swinging in of the lever against the pressure of this spring 34 is accomplished by a stationary cam 38 over which an anti-friction roller 39 on the lever travels as the carrier starts on its movement away from the magazine. As herein shown this roller is secured to the lever by the same screw 30 which pivotally connects the lever with the link 28, and in Fig. 1 this roller is just beginning to ride up on the cam 38 in the outward travel of the carrier from the magazine.

As soon as the jaws are once closed by the action of the cam 38, they are locked in closed position by a latch 40, located at the right hand front corner of the base plate 15 of the carrier. The latch itself is carried at the upper end of a pair of guide pins 41, which are mounted to slide vertically through apertures in the subjacent corner of the base plate 15, and both the latch and its guide pins are normally pulled downward by suitable means. When the lever 25 is swung out and the carrier jaws are open, the tip of the latch rests upon the top of the extreme forward end of the lever and is thereby held up in raised position and is inoperative. But when the lever 25 is swung in to close the jaws, its extremity moves in beneath a notch in the latch which thereupon immediately drops down over the lever and locks it in its uppermost position with the jaws closed. This locking action takes place, as before stated, immediately after the roller 39 rides up on the cam 38 at the beginning of the stroke of the carrier to the right from the magazine toward the affixing mechanism, and the jaws continue to be thus locked throughout the length of this stroke. But as the limit of the carrier movement in this direction is reached, a pin 46 which projects from a stop head 46^a on the lower ends of both of the guide pins 41, strikes and rides up on a stationary incline 47 and gradually lifts the latch 40 until it is raised clear of the lever 25 and leaves the latter free to move back to open the jaws under the pressure of the spring 34. In order to prevent this unlocking of the jaws from occurring too suddenly and with an undesirable noise and jar to the mechanism, a stationary cam lug 48 projects inwardly from the front of the frame in position for contact with the anti-friction roller 39 on the lever 25 just as the latter is released from the latch and before it swings outwardly to any perceptible extent. The inner end 49 of this cam lug then sustains the pressure of the spring 34 during the reversal of the carrier stroke, the roller 39 rides down an inclined surface 50 of the cam lug and permits the lever to swing back and the jaws to gradually open, under the pressure of this spring 34, until they reach the limit of movement permitted by a stop pin

51 that projects upwardly through a slot in the lever 25 from the subjacent bracket 27 of the carrier base plate.

Obviously in returning to its initial position at the left hand end of the carrier movement, the anti-friction roller 39 must again pass the stationary cam lug 38 by the action of which upon the roller the carrier jaws were closed at the beginning of the right hand stroke, but the cam lug 38 is arranged to be lifted out of the path of the returning roller 39 so that said roller can pass beneath the cam lug without being engaged by the latter during its movement. To this end the cam lug 38 is herein shown as supported at the upper end of a slotted slide 52 which is mounted to move vertically over guide screws 53 on the front of a bracket 54 which projects rearwardly and toward the left from the inner side of the front plate 1 of the frame, this slide 52 having at its upper end a forwardly projecting tongue 55 which extends over the top of the bracket 54 and supports the cam lug 38 at the rear of said bracket. At its lower end the slide 52 is connected by a wrist pin 56 with a lever arm 57 that is pivoted at the front of the main frame at 58. The body or principal length of the lever 57 lies directly above the path of a stud 59 on the outer or front face of the lever 25 (Fig. 21), and as the carrier moves back from right to left, this stud strikes the under surface of the lever 57, and by raising the lever lifts the slide 52 and with it the cam lug 38, far enough to permit the roller 39 to pass beneath the lug without coming in contact with it. Then just before the carrier reaches the limit of its travel to the left, the stud 59 passes from beneath the end of the lever 57, and permits the cam lug 38 to drop down into the path of movement of the roller 39, ready to deflect the roller and close the jaws again in the next movement of the carrier to the right.

One of the essential improvements of the sealing mechanism shown in this application consists in the provision of means whereby the envelop is bent centrally outward on its face side by the pressure which forces the flap to fold clear down into its intended position against the back of the envelop, even though the contents of the latter are so thick as to normally tend to raise the flap unduly. To accomplish this action the envelop is delivered by the carrier between the upper and lower guide plates 150 and 151, of which the latter is flush with and may constitute part of the table of the sealer. These guide plates are then provided with opposed inwardly projecting shoulders 152, the distance between which is less than the width of the envelop for which the machine is set. The front corners of these shoulders 152 are prefer-

ably rounded off to permit the edges of the envelops to readily pass by them but their rear faces are notched at 153 so as to catch the edges of the envelops after they have 5 once reached this position.

The forcing of the envelops between the shoulders 152 is accomplished by a reciprocating pressure plate 154 which, in this instance, is carried by a cross head 155 that 10 slides on fixed guide rods 156 of the frame (Fig. 4). This cross head is connected by a link 157 to the upper end of a vibratory lever 158, the lower end of which is pivoted to a fixed lug 159 of the frame. A stud 160 15 is provided on this lever between its ends and projects into the groove in the periphery of the cam 7 on the crank shaft 2, so that the lever will be vibrated and the presser plate 154 reciprocated once in each 20 revolution of the crank shaft.

The envelop E is delivered between the guide plates 151 by the carrier when the presser plate 154 is retracted. The face of the envelop is turned away from the presser 25 plate, while its partially closed flap inclines downwardly toward the plate, after some such manner as is shown in Fig. 4. The bending of the flap down this far is accomplished by a flap turning plate 161 30 placed just inside of the sealer along the path of the envelops. This flap turner is herein shown as secured to the top plate 150 of the sealer by screws 162 (Fig. 33). It 35 consists of a horizontal top plate provided at its left hand end with an upturned lip 163 (Fig. 2), and made wider at this end and provided with a downwardly extending vertical flange 164 which slants back toward the die plate as it approaches the sealer. 40 When the envelop reaches the flap turner in the movement of the carrier toward the sealing mechanism, its flap is in the same substantially horizontal position which it occupied in the magazine, or if sprung up the 45 lip 163 serves to depress it into this horizontal position. Then as the envelop passes beneath the turning plate, the edge of its flap strikes the edge of the flange 164 and is thereby gradually turned down until the 50 envelop emerges into the sealer with its flap folded as closely against the body of the envelop as the thickness of its contents will permit.

Immediately the envelop enters the sealer 55 the presser plate 154 is advanced and strikes the point of the downwardly inclined flap and gradually closes its down against the body of the envelop. The advance of the presser plate causes the envelop to bow or 60 belly outwardly away from the plate as it is pushed between the shoulders 152 which restrain its top and bottom edges. This bending of the envelop takes place just at the right time to permit the point of the 65 flap to slide down the plate, which is pref-

erably inclined backward slightly, until it reaches a substantially vertical position before the actual adhesion between the flap and the bottom of the envelop begins, and the result is that the envelop is fully closed 70 and the flap properly sealed, even though the contents of the envelop are of considerable thickness.

The presser plate 154 is narrow enough vertically to pass freely between the shoulders 152 and eventually forces the envelop through these shoulders against the resistance of two yielding wings or gates 165 (Fig. 3). These gates are pivotally mounted on studs 166 located at each side of the 80 sealer table, being secured to sleeves 167 which rotate freely on these studs. The lower ends of these sleeves serve as drums around which rubber bands 168 may be coiled, and these bands are carried back and 85 adjustably secured by screw bolts 169 to lugs 170 on the table. Said bands are stretched to a suitable degree of tension and serve to swing the gates 165 in against the envelops and then hold them compressed 90 against the presser plate or the notches faces 153 of the shoulders 152. Then as the envelops accumulate the straps yield and permit the gates to open gradually until the envelops pass out beyond them. The vertical 95 distance between the faces of the top and bottom plates 150 and 151 of the sealer back of the shoulders 152 is desirably made less than the height of the envelops so that the bowed position of each envelop is maintained until it is pushed through beyond the top plate 150, thus giving the mucilage on the flap a chance to dry before the natural straightening of the envelop when released 100 from restraint can put strain enough upon the flap to break the seal. This vertical distance and the distance between the shoulder 152 may be adjusted to suit different widths of envelops by raising or lowering the top plate 150 by means of thumb screws 171 on 105 a stud 172 at the outer edge of the sealer table, by which the top plate is supported.

The moistening of the envelop flaps is herein shown as accomplished by a roller 175 located just to the left of the stamp 115 affixing platen. This roller is revolvably mounted in a tank 176, and it is contemplated that the lower portion of the roller shall dip continuously in the water in the tank and that the roller shall be rotated fast 120 enough to keep its upper portion, which projects out of the water, just wet enough to properly moisten the flap. To this end a ratchet wheel 177 is secured on the end of the roller shaft, and a ratchet arm 178 is 125 pivotally mounted on the shaft to carry a ratchet pawl 179. The outer end of this arm is connected by a link 180 with the lever 57 of the carrier mechanism and is thus caused to oscillate once with each movement 130

of the carrier. This lever 57 is oscillated vertically by a projection 59 on the carrier which engages the under side of said lever as the carrier reciprocates, as is fully set forth in my application Serial No. 161,280 hereinbefore referred to. Every oscillation of the lever 178 will then cause the pawl 179 to engage and slightly rotate the ratchet wheel and roller, and the latter will thus be kept constantly moistened. A stop pawl 181 serves to hold the roller against reverse rotation when the pawl is retracted by the return movement of the arm.

Having thus fully described my invention, what I claim as new and desire to secure by Letters Patent is:

1. In an envelop sealing machine, means for turning the flap down toward the body of the envelop, means for bending the body 20 of the envelop between its longitudinal edges, and means for pressing the flap against the bent body of the envelop to seal it, substantially as described.

2. In an envelop sealing machine, means for moistening the envelop, means for folding 25 the flap down toward the body of the envelop, means for bending the body of the envelop to further lower the flap, and means for pressing the flap against the body of the envelop to seal it, substantially as described.

3. In an envelop sealing machine, means for moistening the envelop, means for folding the flap down toward the body of the envelop, devices for retarding the envelop 35 along opposite edges, and envelop bending means engaging the envelop between the retarding devices and pressing the flap against the body of the envelop to seal it, substantially as described.

4. In an envelop sealing machine, means for bending the body of the envelop in a direction transverse to the attached margin 40 of the flap, to force the flap against the body of the envelop, and means for pressing the flap against the envelop while in this position to seal it, substantially as described.

5. In an envelop sealing machine comprising means for feeding the envelops, and means for moistening them, a combined 50 sealer and stacker comprising a stacker table, means for pushing the envelops on to the stacker table, obstructions which intercept the envelops while being pushed on to the table, and cause them to bend, said obstructions also preventing the envelops from returning from the stacker table, and means for pressing the envelops to seal them, substantially as described.

6. In an envelop sealing machine the combination of means for feeding the envelops, means for moistening them, means for bending the bodies of the envelops and means for compressing the envelops to seal them while in a bent position, substantially as described.

7. In a machine for sealing envelops and the like, the combination of means for feeding the envelops, means for moistening them, a stacker table, means for pushing the envelops on to the stacker table, obstructions 70 for bending the envelops as they are being pushed on to the stacker table, and means for compressing the envelops while in a bent position, substantially as described.

8. In a machine for sealing envelops and 75 the like, the combination of means for feeding the envelops, means for moistening them, a stacker table, means for pushing the envelops on to the stacker table, stationary 80 obstructions for bending the envelops as they are being pushed on to the stacker table, and means for compressing the envelops while in a bent position, substantially as described.

9. In a machine for sealing envelops and 85 the like, the combination of means for feeding the envelops, means for moistening them, a stacker table, means for pushing the envelops on to the stacker table, obstructions 90 for bending the envelops as they are being pushed on to the stacker table, means for adjusting said obstructions to cause more or less bending of envelops, and means for compressing the envelops while in a bent position, substantially as described.

10. In an envelop sealing machine the combination of means for feeding the envelops, means for moistening them, means for bending the envelops, said bending 100 means being adjustable to cause more or less bending of the envelops and means for pressing the envelops while in a bent position, substantially as described.

11. In a machine for sealing envelops or the like, means for bending the body of the 105 envelop in a direction transverse to the attached margin of the flap to force the flap down against the body of the envelop ready for sealing, means for adjusting the bending means, so as to cause more or less bending of the envelop, substantially as described and means for folding the flap against the body of the envelop and sealing and stacking the envelop in one operation.

12. In a machine for sealing envelops or the like, comprising a moistener, means for bending the moistened envelops, means for pressing the moistened envelops while in a bent position, and means for holding the envelops in a bent position to allow the 110 moisture to partially dry before they are allowed to straighten up, substantially as described.

13. In a machine for sealing envelops or the like, comprising a moistener for moistening the flaps of the envelops, means for bending the moistened envelops, means for pressing the moistened envelops, while in a bent position, and means for holding the envelops in a bent position to allow the 120 130

moisture to dry before they are allowed to straighten, substantially as described.

14. In a machine for sealing envelopes or the like, the combination of means for feeding the envelopes, means for moistening them, means for bending the bodies of the envelopes in a direction transverse to the attached margin of the flap preparatory to sealing, and means for compressing the envelopes, substantially as described.

15. In an envelop sealing machine comprising means for feeding the envelopes, and means for moistening them, a combined sealer and stacker, comprising a stacker table, means for pushing the envelop on to the stacker table, obstructions for bending the envelop, and means for compressing the envelopes to seal them, substantially as described.

20 16. In a machine for sealing envelopes and the like, the combination of a table for receiving the envelopes, means for moistening the envelopes, a table on which the envelopes are stacked or bunched, means for carrying the envelopes from the receiving table past the moistener to a position in front of the stacker table, means for pushing the envelopes on to the stacker table, obstructions for causing the envelopes to bend as they are being pushed on to the stacker table, and means for compressing the envelopes while on the stacker table, substantially as described.

35 17. A machine for sealing envelopes or the like comprising means for feeding the envelopes, means for moistening them, means for bunching or stacking them, means in the stack for yieldingly holding the sealed envelopes therein under a suitable pressure, said means releasing the envelopes at the rear of the stack after a predetermined quantity has accumulated therein.

40 18. A machine for sealing envelopes and the like comprising means for feeding the envelopes, means for moistening them, means for bunching or stacking them, means in the stacker for holding a predetermined quantity of said envelopes under pressure, said means releasing the envelopes as they accumulate in the stacker over and above the said predetermined quantity.

45 19. In an envelop sealing machine, means for moving the envelop, means for moistening the envelop, means for folding the flap down toward the body of the envelop, obstructions for bending the body of the envelop to further lower the flap, and means for compressing the envelop while in a bent position, substantially as described.

50 20. In a machine for sealing envelopes and the like, the combination of means for feeding the envelop, means for moistening it, means for pushing the envelop sidewise, obstructions for bending the body of the envelop as it is being pushed sidewise, and

means for compressing the envelop while in a bent position, substantially as described.

55 21. In an envelop sealing machine, a flap moistening mechanism, a stack to receive envelopes, a stacking device adapted to move the envelopes into said stack, means for delivering the envelopes to the stacking device with the flap toward the stacker, whereby the stacker will primarily press the flap against the body of the envelop and will then force the envelop directly into the stack, and yielding means for holding the envelopes in the stack.

60 22. An envelop sealing machine comprising a flap moistening means, a stack or receiver, a sealing and stacking mechanism adapted to move the envelopes bodily into the stack, a feeding means to deliver the envelopes to the sealing and stacking mechanism with the flaps unsealed, whereby the said sealing and stacking mechanism will seal and stack the envelopes in one operation.

65 23. In an envelop sealing machine the combination of means for feeding envelopes, means for moistening the flaps thereof, means for bending the bodies of the envelopes, and means for compressing the envelopes and forcing them into a stack while in a bent position.

70 24. In an envelop sealing machine means for bending the body of the envelop so that the bending operation will cause the flap to tend to hug closely against the body of the envelop in position for sealing, and means for pressing the flap against the envelop while in this position to seal it and to force the envelop into a stack.

75 25. An envelop sealing means comprising a reciprocating envelop feeding means, a flap moistening means adapted to moisten the flaps of the envelopes as they are moved by the feeding means, a stack, a reciprocating sealing and stacking device operating across the path of the envelopes as they are moved by the feeding means and yielding means for holding the envelopes in the stack said means releasing envelopes from the stack after a certain amount has been accumulated therein.

80 26. A machine for sealing envelopes comprising a stack, means for sealing and stacking envelopes, said means forcing the envelopes bodily into the forward end of the stack, and yielding means for holding the envelopes in the stack, said means releasing envelopes from the stack after a certain amount has been accumulated therein, said releasing means permitting the envelopes to be released at the back of the stack as envelopes are forced into the stack at the forward end thereof.

85 27. An envelop sealing means comprising a reciprocating envelop feeding means, a flap moistening means adapted to moisten the flaps of the envelopes as they are moved

- by the feeding means, a stack, a reciprocating sealing and stacking device operating across the path of the envelops as they are moved by the feeding means, yielding means 5 for holding the envelops in the stack, said means releasing envelops at the back of the stack after a predetermined amount has been accumulated therein, said releasing means being operated by the stacking device.
- 10 28. An envelop sealing machine comprising an envelop moistening means, an envelop feeding means, a sealing and stacking mechanism and means to separate the mois-

tened flap from the body of the envelop as the envelop enters the stack, whereby the 15 sealing and stacking mechanism will force the envelop flap against the body of the envelop and then force the envelop into the stack.

In testimony whereof I hereunto affix my 20 signature in the presence of two witnesses.

LOUIS J. HALL.
